Attorneys

UNITED STATES PATENT OFFICE.

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK.

SLICING MACHINE.

Application filed September 8, 1928. Serial No. 304,764.

My invention relates to a slicing machine having a rotary knife and relates particularly to a knife guard for such slicing machine. One object of my invention is to provide a guard which shall cover the forward side of the exposed cutting arc of a rotary knife. Another object is the provision of such a guard which may be applied to a work carriage traveling across the face of said knife. Another object is the provision of such a guard which shall cover or guard the cutting edge of the knife when the carriage reaches the end of its cutting excursion and when the work has been carried past the cutting edge of the knife. Other objects will appear from time to time in the course of the specification and claims.

I illustrate my invention more or less diagrammatically in the accompanying drawings, wherein—

Figure 1 is a front elevation; and

Figure 2 is a section on the line 2—2 of Figure 1.

Like parts are indicated by like symbols throughout the specification and drawings.

A generally indicates any suitable base upon which is mounted the rotary knife A¹ which may be actuated through the pulley A² and belt A³ from the driving pulley A⁴ on a shaft A⁵ which may be rotated for example by an electric motor or any other suitable prime motor, not herein shown. It will be observed from the drawings that the knife A¹ lies in a generally vertical plane, its axis of rotation being horizontal. This axis however is slightly tilted, in the horizontal plane, to throw the cutting edge or arc of the knife forwardly, as shown in Figure 2, the plane of the knife being thus somewhat inclined to the plane of the forward guard plate B.

C¹ indicate tracks along which runs the meat carriage generally indicated as C², which includes the work supporting surface C³ and the upstanding flange C⁴ along one edge thereof. C⁵ is any suitable handle whereby the work supporting carriage may be reciprocated across the cutting plane of the knife.

D indicates a gauge plate mounted on the support D¹ which may be moved toward

and away from the cutting plane of the knife as by rotation of the handle D².

E indicates a guard member, herein shown as roughly arcuate in shape. It is secured by means of the flange E¹ and the screws E², to the upstanding flange C⁴ of the meat supporting surface C³. In order that the work may be cut it is necessary that the cutting arc of the knife be exposed, as shown for example in Figure 1. However it is desirable that this cutting arc be protected or covered when the necessity for exposing it has passed. When the carriage is in the full line position of Figure 1 the cutting arc is exposed and operates against whatever material is placed upon the carriage and thrust into position against the gauge plate. When the carriage is moved forwardly toward the knife edge, from left to right, as shown in Figure 1, the work is carried across the face of the knife and the slice is severed by the rotation of the knife. When the cutting reciprocation continues and the work supporting carriage is carried to the dotted line position of Figure 1, then the guard E overlies and masks the cutting arc. As shown in Figure 2 the edge of the gauge plate masks the cutting arc from the rear and the arc E masks it from the front and when the carriage is in dotted line position it is practically impossible for an operator to cut his hand unless he actually inserts his fingers between gauge plate and guard, a most unlikely performance.

I claim:

1. In association with a slicing machine including a rotary knife and means for rotating it and a work supporting member guided across the face of the knife, a guard adapted to mask the cutting edge of the knife from the work support side, and means for positioning said guard in operative position at the termination of the cutting excursion of the work support.

2. In association with a slicing machine including a rotary knife and means for rotating it and a work supporting member guided across the face of the knife, a guard adapted to mask the cutting edge of the knife, and means for positioning said guard in operative position at the termination of the

the cutting excursion of the work support.

3. In association with a slicing machine including a rotary knife and means for rotating it and a work supporting member

5 guided across the face of the knife, a guard mounted upon said work supporting member and adapted to mask the cutting edge of the knife when the work supporting member has passed across such cutting edge.

10 4. In association with a slicing machine including a rotary knife and means for rotating it and a work supporting member and means for guiding it across the face of the knife, a guard mounted upon and projecting

15 upwardly from said work supporting member, adapted to mask the cutting edge of the knife when the work supporting member has been moved across said cutting edge.

5. In association with a slicing machine

20 including a rotary knife and means for rotating it and a work supporting member and means for guiding it across the face of the knife, a guard mounted upon and projecting upwardly from said work supporting member, adapted to mask the side of the cutting edge toward the work supporting member when the work supporting member has been moved across said cutting edge.

6. In association with a slicing machine

30 including a rotary knife and means for rotating it and a work supporting member and means for guiding it across the face of the knife, a guard associated with said work supporting member, adapted to mask the side of the cutting edge of the knife toward the work supporting member when the work supporting member has been moved across said cutting edge.

7. In association with a slicing machine

40 including a rotary knife and means for rotating it and a work supporting member and means for guiding it across the face of the knife, a guard associated with said work supporting member, adapted to mask the side of the cutting edge of the knife toward the work supporting member when the work supporting member has been moved across said cutting edge, said guard including a

45 plate positioned upon and movable with said work supporting member, lying in a plane generally parallel with the path of movement of the work supporting member and in front of the knife edge.

8. In association with a slicing machine

55 including a rotary knife and means for rotating it and a work supporting member and means for guiding it across the face of the knife, a guard, mounted upon said work supporting member, adapted to mask the cutting edge of the knife.

9. In association with a slicing machine

65 including a rotary knife and means for rotating it and a work supporting member and means for guiding it across the face of the knife, a guard, mounted upon said work

supporting member, adapted to mask the cutting edge of the knife, said guard being positioned on the same side of the knife edge as the work supporting member.

10. In association with a slicing machine

70 including a rotary knife and means for rotating it and a work supporting member and means for guiding it across the face of the knife, a guard associated with said work supporting member, adapted to mask the

75 side of the cutting edge of the knife toward the work supporting member when the work supporting member has been moved across said cutting edge, said guard including a plate positioned upon and movable with said

80 work supporting member, said plate extending outwardly beyond the periphery of the knife, when in operative position.

11. In association with a slicing machine

85 including a rotary knife and means for rotating it and a work supporting member and means for guiding it across the face of the knife, a guard associated with said work supporting member, adapted to mask the side of the cutting edge of the knife toward

90 the work supporting member when the work supporting member has been moved across said cutting edge, said guard including a plate positioned upon and movable with said

95 work supporting member, said plate extending outwardly beyond the periphery of the knife, when the work supporting member is at the termination of its working stroke.

12. In association with a slicing machine

100 including a rotary knife and means for rotating it and a work supporting member movable across the face of the knife, a guard, mounted on the edge of said supporting member remote from the knife when the supporting member is in initial position,

105 such guard being adapted to overlie and mask the cutting edge of the knife from the work support side at the termination of the cutting excursion of the work support.

13. In association with a slicing machine

110 including a rotary knife and means for rotating it and a work supporting member movable across the face of the knife, a guard, mounted on the edge of said supporting member remote from the knife when

115 the supporting member is in initial position, such guard being adapted to overlie and mask the cutting edge of the knife from the work support side at the termination of the cutting excursion of the work support, the

120 forward edge of the work supporting member closely approaching the cutting plane of the knife, said guard lying substantially in the plane of said forward edge.

14. In association with a slicing machine

125 including a rotary knife and means for rotating it and a work supporting member and means for guiding it across the face of the knife, a guard mounted upon said work supporting member and adapted to mask the

130

cutting edge of the knife when the work member, the guard being associated with supporting member has passed across such said flange.

cutting edge, a work engaging flange, generally perpendicular to the cutting plane of the knife, lying along the edge of the work supporting member remote from the knife at the initial position of said work supporting

Signed at Indianapolis, county of Marion ¹⁰ and State of Indiana, this 31st day of August, 1928.

WILLIAM J. CAMPBELL.
